UNITED STATES PATENT OFFICE.

ANTHONY KIRSCH, OF BROOKLYN, NEW YORK, ASSIGNOR TO WILSON BOHANNEN, INC.,
OF BROOKLYN, NEW YORK, A CORPORATION OF NEW YORK.

LOCK.

1,272,967.

Specification of Letters Patent. Patented July 16, 1918.

Application filed November 10, 1917. Serial No. 201,323.

To all whom it may concern:

Be it known that I, ANTHONY KIRSCH, a citizen of the United States, and a resident of the city of New York, borough of Brooklyn, in the county of Kings and State of New York, have invented a new and Improved Lock, of which the following is a full, clear, and exact description.

The invention relates to door locks consisting essentially of a key-controlled cylinder lock at the outside of the door and controlling a latch lock on the inside of the door.

The object of the invention is to provide a new and improved lock arranged to permit of fastening it correctly in position on either a right or left hand door, at the same time insuring proper alinement of the cylinder lock and the latch lock.

In order to accomplish the desired result use is made of a key-controlled cylinder section having threaded lugs, a latch bolt section having a casing provided with two sets of apertures either of which is adapted to register with the said threaded lugs according to which side of the door lock is to be used, and connecting screws extending through the registering set of apertures and screwing into the said threaded lugs. Use is also made of a rollback having a hub, arms mounted to swing on the said hub, and means limiting the swinging movement of the arms.

A practical embodiment of the invention is represented in the accompanying drawings forming a part of this specification, in which similar characters of reference indicate corresponding parts in all the views.

Figure 1 is an inverted sectional plan view of the lug as applied, the section being on the line 1—1 of Fig. 2;

Fig. 2 is a cross section of the same on the line 2—2 of Fig. 4;

Fig. 3 is a face view of the latch lock on the inside of the door;

Fig. 4 is a rear sectional view of the same on the line 4—4 of Fig. 2 and showing the latch;

Fig. 5 is a similar view of the same with the latch bolt in retracted position;

Fig. 6 is a perspective view of the rollback for the latch bolt and controlled by a knob on the inside of the lock; the several parts being shown in disassembled position;

Fig. 7 is a face view of a portion of the back plate.

The lock in its general construction consists of a key-controlled cylinder section 10, a latch bolt section 11 having a latch bolt 12 adapted to engage a keeper 13 attached to the door jamb 14 adjacent the door 15, of which the key-controlled cylinder section 10 is held on the outer face and the latch bolt section 11 is fastened to the inner face thereof by screws 16. The casing 20 of the cylinder section 10 is provided with the usual key-controlled plug 21 and with an integral face plate 22 engaging a ring 23 resting against the outer face of the door 15. The casing 20 extends into an aperture 24 formed in the door 15, and the casing is provided at opposite sides with integral lugs 30, 31 in which screw the screws 32, 33 extending through either set of apertures 34, 35 or 36, 37 formed in the back plate 38 of the casing 39 of the latch bolt section 11. The screws 32 and 33 also pass through a corresponding registering set of apertures 40, 41 or 42, 43 formed in the integral front plate 44 of the casing 39, and the heads 45 and 46 of the screws 32, 33 are countersunk in apertures 47, 48 formed in a disk 49 arranged on the front plate 44 of the casing. The disk 49 is mounted to turn on a hub 50 mounted to turn in a bearing 51 formed integrally on the front plate 44, and the hub 50 is provided with knob 52 under the control of the operator for retracting the latch bolt 12 whenever it is desired to do so and as hereinafter more fully explained. The hub 50 forms parts of the rollback having two arms 53, 54 extending from rings 55, 56 mounted to turn on the hub 50. The rings 55, 56 are provided with inwardly extending lugs 57, 58 engaging slots 59, 60 formed diametrically opposite each other in the hub 50 thus limiting the swinging motion of the arms 53 and 54 on the hub 50. A washer 61 is riveted or otherwise fastened on the hub 50 adjacent the ring 56 to hold the several parts in position. The arms 53 and 54 are adapted to engage flanges 65 and 66 on a fork 67 secured to or forming part of the latch bolt 12, which latter is pressed on in the usual manner by a spring 68 to normally hold the latch bolt in locking position, that is, in engagement with the keeper 13. The slots 59 and 60 in the hub 50 are arranged intermediate the corresponding sets of apertures 40, 41, 42, 43, and the latter are grouped around the bearing 51 (see Figs. 4, 5 and 6) so that the arms 53, 54 are out of engagement with

the screws 32, 33 whether the latter engage one set or the other set of said apertures. Thus when the several parts are in the position shown in Fig. 4 and the knob 12 is turned 5 in one direction then the arm 53 acts on the flange 65 and retracts the latch bolt 12, and when the knob 52 is turned in the opposite direction then the arm 54 acts on the flange 66 and retracts the latch bolt 12. The casing 10 39 is provided with integral stop lugs 70, 71 to limit the movement of the yoke 67 when retracting the latch bolt 12. The said stop lugs 70, 71 also serve as stops for the arms 53, 54 to prevent the same from coming 15 in contact with the bolts 32, 33.

The flanges 65, 66 are adapted to be engaged by a set of arms 80, 81 similar to the arms 53, 54 and having rings 82, 83 mounted to turn on a hub 84 mounted to turn in a 20 bearing 85 formed on the back plate 38. The hub 84 is engaged in the usual manner by the spindle 85 turning with the plug 21 of the cylinder section 10 to retract the bolt 12 without turning the key in the plug 25 21 the same as the operator turns the knob 52, as previously explained. It is understood that the hub 84 is provided with slots 59, 60 the same as the hub 50, and the rings 82, 83 are provided with lugs 57, 58 engaging 30 the said slots 59 and 60 to limit the swinging movement of the arms 80, 81 on the hub 84.

It is understood that in attaching the lock to the door 15, the plug 21 is in correct position when downward, as indicated in Fig. 2, and hence when the lock is used on a right hand door then the screws 32, 33 engage the sets of apertures 34, 35, 40, 41 and the apertures 47, 48 in the disk 49.

40 When the lock is applied to a left hand door then the disk 49 is given a half turn to move the apertures 47, 48 in register with the apertures 42, 43, and the bolts 32, 33 are now engaged with the said apertures 47, 48, 45 42, 43 and 36, 37 with the threaded ends of the screws screwing in the lugs 30, 31.

From the foregoing it will be seen that by the arrangement described the lock can be correctly attached to either a right or 50 left hand door and in either case the plug 21 is in correct downward position.

It is understood that when the screws 32, 33 are screwed up the cylinder section 10 is firmly drawn in position on the outer 55 face of the door 15 thus holding the cylinder section in place without any screws appearing on the outside of the door.

Having thus described my invention, I claim as new and desire to secure by Letters Patent:—

1. A door lock, comprising a key-con-

trolled cylinder section having threaded lugs, a latch bolt section having a casing provided with a back plate and a front plate, the said back and front plates having sets 65 of registering apertures either of which is adapted to register with the said threaded lugs, and connecting screws extending through a set of registering apertures in the said back and front plates and screwing 70 into the said threaded lugs.

2. A door lock, comprising a key-controlled cylinder section having threaded lugs, a latch bolt section having a casing provided with two sets of apertures either 75 of which is adapted to register with the said threaded lugs, a bolt slidable in the said casing, two rollbacks each having a hub and arms having limited swinging movement on the hub, the hub of one rollback being controlled by the cylinder section and the hub of the other rollback having a manually controlled knob, and connecting screws extending through the registering set of apertures and screwing into the said threaded 80 lugs, the said screws being out of the paths of the said arms.

3. In a door lock, a rollback having a hub provided with a diametrical slot, arms having rings mounted to turn on the said 90 hub, the arms extending in opposite directions, the rings having lugs extending into the ends of the said slot, the lugs being narrower than the slot, the arms in one position being diametrically opposite each 95 other and in another position extending at an angle one relative to the other.

4. A door lock, comprising a key controlled cylinder section having threaded lugs, a latch bolt section having a casing 100 provided with two sets of apertures either of which is adapted to register with the said threaded lugs, a bolt slidable in the said casing, two rollbacks each having a hub and arms having limited swinging movement on the hubs, the hub of one rollback being controlled by the cylinder section and the hub of the other rollback having a manually controlled knob, a disk mounted to turn on the hub having the knob, the 105 disk having apertures adapted to register with either set of casing apertures on correspondingly turning the disk, and connecting screws extending through the said disk apertures, and the casing apertures in register with the disk apertures at the time, the screws screwing in the said threaded lugs and being out of the paths of the said arms.

ANTHONY KIRSCH.
